UNITED STATES PATENT OFFICE.

ANDREW TUITE, OF VINCENNES, INDIANA, ASSIGNOR TO JOHN J. TUITE, OF VINCENNES, INDIANA.

GLASS-DRAWING APPARATUS.

1,020,858.

Specification of Letters Patent. Patented Mar. 19, 1912.

Application filed September 27, 1909. Serial No. 519,717.

To all whom it may concern:

Be it known that I, ANDREW TUITE, a citizen of the United States, residing at Vincennes, in the county of Knox, State of Indiana, have invented certain new and useful Improvements in Glass-Drawing Apparatus; and I do hereby declare the following to be a full, clear, and exact description of the invention, such as will enable others skilled in the art to which it appertains to make and use the same.

This invention relates to glass drawing apparatus and particularly to that type in which the drawing operation is effected mechanically.

The object of the invention resides in an improved construction of apparatus of the character named which will be exceedingly simple and efficient in operation and which will enable the drawing operation to be accomplished by a single operator located at a given fixed point.

In forming glass cylinders it is necessary to provide for a release of air pressure after the cap of same is made.

It is therefore a further object of this invention to provide means for reducing the air pressure during the operation of drawing when it is no longer possible to maintain the initial pressure in the furtherance of the proper execution of the work.

A still further object of the invention is to provide electrically operated means for disconnecting the drawing carriage from the mechanism for positively lifting and lowering same, whereby said carriage may be lowered at the will of the operator independently of the actuation of said mechanism.

To this end the invention consists in the details of construction and in the arrangement and combination of parts to be herein after more fully set forth and claimed.

In describing the invention in detail reference will be had to the accompanying drawings in which like characters of reference denote corresponding parts in the several views, and in which,

Figure 1 is a diagrammatic view illustrating the improved drawing apparatus and the various electrical connections utilized in the operation of same; Fig. 2, a top plan view of the motor and connections for positively raising and lowering the drawing carriage; Fig. 3, a longitudinal section of the

reservoir which is located in the pipe line between the compressed air supply and the blow pipe; and, Fig. 4, a detail view of the drawing carriage.

In these drawings the drawing carriage of the apparatus comprises a frame with side bars 5 and 6 and top and bottom bars 7 and 8 provided with guide blocks 9 and 10 which it will be understood travel on the vertical guide bars 11 and 12 respectively, as the drawing carriage is raised and lowered. A supporting member 13 connects the guide bars 5 and 6 and is provided intermediate bars 13' at its ends with an opening 13" through which passes a blow pipe 14 this blow pipe 14 also extends through apertures formed in the top and bottom bars 7 and 8 and has adjustably secured to its intermediate point a sleeve 14'. As will be apparent from Fig. 4 of the drawings the blow pipe is formed in two sections the adjacent ends of which are threaded for engagement by the sleeve which not only serves to permit of the slight adjustment of the said sleeve, but also as a connection between the pipe connections 80. The sleeve 14' is arranged to slide loosely in a collar 15 formed upon the upper face of the supporting bar 13 which retains the blow pipe in its normal position limiting its downward movement. Arranged directly beneath the drawing carriage is a glass holding receptacle 16, so that a movement of said carriage on the guide rails 11 and 12, will cause same to approach and recede from said glass holding receptacle. A pair of cables 17 and 18 have their lower ends secured to the top bar 7 of the draw carriage and are carried upwardly around the pulleys 19 and 20 respectively and thence over other suitably located pulleys to the drum 21 upon which said cables are adapted to be wound and unwound. Said drum is mounted on a shaft 22 which is journaled in the standards 23 and 24. Said shaft also carries a gear 25 which meshes with the gear 26, said last named gear being loosely mounted on the shaft 27 which is likewise journaled in the standards 23 and 24. On the end of the shaft 27 opposite that on which the gear 26 is mounted is a worm wheel 28 which meshes with a worm 29 on the shaft 30 of the electric motor 31. Keyed to the shaft 27 and adapted for a sliding movement longitudinally thereof is a clutch member 32. A spring 33 having one end en-

gaging a collar 34 on said shaft 27 and the other end abutting the clutch member 32 constantly tends to force said member 32 into locking engagement with the corresponding clutch member 33 which is fixed to the gear 26. It will thus be obvious that when the motor 31 is operated in one direction, the clutch members 32 and 33 being in locking engagement, the drum 21 will be rotated and the drawing carriage will be elevated, and it will be likewise apparent that when the direction of rotation of the motor 31 is reversed the drawing carriage will be lowered. It is sometimes desirous, however, to quickly and effectively lower the drawing carriage without actuating the mechanism just described for that purpose. To this end there is secured to the clutch member 32 the arm 35 of the pivoted angular armature 36. Disposed adjacent said armature is a magnet 37 which when energized is adapted to attract the armature 36 and thereby impart to the clutch member 32 a movement away from the clutch member 33 and release the locking engagement between said members. When this operation has taken place the drawing carriage by reason of its weight will automatically descend; the drum 21 being then free to rotate independently of the motor 31 and the various other connections. The energization of the magnet 37 is controlled by the electric switch 38 located at the operator's table 39 and connected with said magnet by suitable conductors 40 and 41.

The starting and stopping of the motor 31 is instituted by the controller 42 mounted on the operator's table 39, said controller being electrically connected with the motor 31 by the connections 43, 44, 45 and 46; while the direction of rotation of said motor is reversed through the medium of a switch 47 also located on the operator's table.

Compressed air from a suitable supply 45 (not shown) is transmitted through the blow pipe 14 by means of the pipe line connection which comprises the pipe sections 48 and 49 and a reservoir 50, the section 48 communicating at one end with the interior 50 of the reservoir 50 and at the other end with the compressed air supply (not shown). The section 49 has its lower end resting upon the upper end of the blow pipe 14, the construction of the engaging ends of the 55 blow pipe 14 and the section 49 being such that the weight of the latter produces a substantially air tight connection at said point of engagement. The reservoir 50 comprises a casing having its upper end closed 60 and its lower end provided with a stuffing box 51, the pipe section 48 entering said reservoir intermediate its closed end, and said stuffing box, and the pipe line section 49 has its upper end extending through said 65 stuffing box and into the interior of the res-

ervoir. The length of the reservoir 50 is such that the open end of the pipe section 49 will always be confined in the interior thereof as the draw carriage is moved up and down during the operation of drawing the glass. The pipe section 48 has provided therein a vent pipe 53 which is provided with a valve 54 by which communication with the atmosphere from the said pipe section 48, through the vent pipe 53 is controlled. Also located in said pipe section 48 is a stop-cock 55 through the utilization of which the supply of compressed air to the blow pipe 14 may be entirely cut off. It will be noted that both the valve 54 of the vent pipe 53 and stop-cock 55 are located adjacent the operator's table 39 so as to permit the convenient and ready operation thereof by the operator during the manipulation of the electrically operated means for raising and lowering the draw carriage.

From the foregoing construction it will be readily apparent that the number of workmen required in the operation of the apparatus is reduced to a minimum as the operator stationed at the table 39 is enabled, not only to effect the raising and lowering of the draw carriage with promptness and facility but also to control the reduction in air pressure during the operation of the apparatus by the opening of the vent pipe 53 to a desired extent.

The operation of the apparatus is as follows:—Assuming the carrier 7 to be in the position shown in Fig. 1 of the drawings 100 it is only necessary in order to institute the operation of drawing to close the switch 47 and position the switch 42 to operate the motor 30 in such a direction as will rotate the drum 21 to elevate the carrier 7. During the elevation of said carrier it will of course be understood that compressed air from a suitable supply is passing through the pipe 48, reservoir 51, pipe 49 and blow pipe 14; the passage of said compressed air 110 serving to form the desired glass object on the bait of the blow pipe. It will be further apparent that during the elevation of the pipe 47 the upper end of the pipe 49 will move into the reservoir 50 and thus 115 permit the elevation of the carrier 7 without interference or the employment of a flexible connection between the blow pipe 14 and the compressed air supply. When the elevation of the carrier 7 is instituted the vent 120 54 is closed and the pressure of the compressed air traveling through pipe 49 is equivalent to the pressure of the air supply. However, as it is essential in producing 125 glass objects of certain forms that the pressure of air be reduced, as the drawing of the object proceeds the vent 54 may be opened and thus reduce the pressure of air passing through the pipe 49 below the pressure in the supply. In cases where it is not 130

necessary to reduce the pressure during the process of drawing the vent is employed to maintain a given pressure when a certain amount of air in the reservoir 50 is displaced 5 by the entrance of the upper end of the pipe 49 therein.

In order to lower the carrier 7 without stopping the motor 31 the electrically operated clutch is utilized by the operation of 10 the switch 38; it being apparent from an inspection of Figs. 1 and 2 that the energization of the magnet 37 will throw out said clutch, while the spring 33 will serve to automatically throw in the clutch when the 15 magnet 37 is not energized.

It will be noted that while one particular way of carrying the invention into practice has been shown and described it will be obvious that various changes in the 20 details of construction and in the arrangement and combination of parts may be resorted to without in any manner departing from the scope thereof.

What I claim is:—

25 The combination in a glass drawing apparatus, of a base, spaced guides extending

vertically therefrom, a frame slidable upon said guides, said frame consisting of vertical and longitudinal bars, a drawing tube 30 slidable through the frame, a sleeve formed upon one of said bars and surrounding the drawing tube, said sleeve being greater in diameter than the opening in the bar which surrounds the drawing tube, a stop adjustable upon the drawing tube for engagement 35 with the shouldered lower end of the sleeve, cables secured to opposite ends of the frame upon opposite sides of the drawing tube, guide sheaves engaging the cables and a winding drum for the cables, a telescoping 40 tube engaging the upper end of the drawing tube, the interior of said tube being provided with circular recesses, a pipe extending from one of said recesses and a vacuum attachment for the pipe. 45

In testimony whereof, I affix my signature, in presence of two witnesses.

ANDREW TUITE.
